CLAIM

The ornamental design for a box, as shown and described.

DESCRIPTION

FIG. 1 is a perspective view of a box showing my new design in a partially assembled open top and bottom configuration;

FIG. 2 is a top perspective view of the box of FIG. 1 in an alternate partially assembled open top configuration;

FIG. 3 is a front view of the box shown in FIG. 1;

FIG. 4 is a back view of the box shown in FIG. 1;

FIG. 5 is a right side view of the box shown in FIG. 1;

FIG. 6 is a left side view of the box shown in FIG. 1;

FIG. 7 is a top view of the box shown in FIG. 1;

FIG. 8 is a bottom view of the box shown in FIG. 1;

FIG. 9 is a top perspective view of the box of FIG. 1 in an assembled and closed configuration;

FIG. 10 is a bottom perspective view thereof;

FIG. 11 is a front view thereof;

FIG. 12 is a back view thereof;

FIG. 13 is a right side view thereof;

FIG. 14 is a left side view thereof;

FIG. 15 a top view thereof;

FIG. 16 is a bottom view thereof; and,

FIG. 17 is a top plan view of the box of FIG. 1 in an unassembled blank configuration, showing the interior planes of the box.

The broken lines shown in the drawings illustrate fold lines and form no part of the claimed design.

1 Claim, 15 Drawing Sheets
